METHOD OF WOOL PULLING AND SORTING

Stanley S. Steinharter, Cincinnati, Ohio, assignor of one-fifth to Augusta K. Steinharter and one-fifth to Carlisle Y. Steinharter, both of Cincinnati, Ohio, and one-fifth to N. Parker Swift, one-fifth to E. N. Morang, and one-fifth to Al West, all of Detroit, Mich.

Application January 15, 1944, Serial No. 518,455

3 Claims. (Cl. 19—2)

This invention relates to methods of pulling or otherwise stripping wool from an animal skin such as a sheepskin and it is also concerned with the problem of wool sorting which is incident to the pulling or stripping. The invention also has an application to the sorting of the various grades of wool contained in a sheared fleece as distinguished from a sheepskin with the wool attached.

In the art of wool pulling generally, for time out of mind it has been the universal practice to proceed substantially as follows: The skin to which the wool is still attached is first thoroughly cleaned and is then treated with a depilating solution of which a representative type is sodium sulphide. After treatment for a fixed period of time sufficient to loosen the hair without causing deterioration of the skin, the skin is then turned over to a skilled hand worker known as a wool puller. In the operation of removing the wool from the skin the wool puller first laps the saturated skin with the hair out over a slanting board known as a "beam." Holding the upper end of the beam against his body he proceeds to strip the wool from the exposed portion of the skin and at the same time sorts it according to recognized grades. The standard procedure is to first strip the back or main grade of wool as this grade is the one most directly exposed to the operator practicing this method. Thereafter the stained and shorter flank wools are removed, followed by the coarse rump wool, and finally the grey leg and head wool. As each grade of wool is removed it is placed in a receptacle intended for the reception of that particular grade.

After half of the skin has been stripped or pulled in this manner the position of the skin on the beam is reversed and the other half is similarly treated. The entire operation of pulling and sorting is in all cases performed by one man working individually. Although termed "pulling" the manual operation can be more accurately described as a pushing operation as the operator holding the end of the beam against his body removes the loosened wool from the skin with an outward movement of his arms and hands.

Very obviously there are a number of objections to this method. Since the grades of wool are not delineated on the skin by any very exact lines of demarcation, it requires a very skillful operator to perform the sorting of the grades with the degree of exactness that is required commercially. It is difficult to train men to do the work properly and, even though the wage scale is very high, there are many who are never

able to learn. Another specific objection is that in removing the back or main portion first by the rather awkward method just described the operator almost invariably mixes certain adjacent portions of the inferior grades with the main portion. Since the presence of even a small amount of inferior wool in the main grade is frequently sufficient to cause the entire main grade to be classified as an inferior grade, this type of mistake may be very costly yet at the same time it is one that is very difficult to avoid.

Aside from the inaccuracy of the sorting results obtained, the beam method is likewise very unsatisfactory because it is slow, cumbersome and exceedingly unpleasant work for the operator.

In the present invention it has been discovered that greatly improved results may be obtained by the use of a method which is almost the exact converse of the beam method. In accordance with the present method, after treatment of the skin in a depilating solution as in the beam method each of the various grades of wool is then removed by one or more operators whose duties are confined to the removal of that particular grade. In addition, the inferior grades are all removed prior to the removal of the main grade as distinguished from the reverse procedure taught by the prior art. In this way there is a double check as to the presence of inferior wool in the main grade as the operators performing the removal of the inferior grades check on it first while the operators removing the main grade check on it after the inferior grades have been removed.

35 The method of the invention preferably contemplates the movement of the skins from one operator to another or one pair of operators to another pair as indicated by the arrows in the drawing. This movement may be performed 40 manually on a table or preferably on a conveyor belt with the operators positioned on one or both sides thereof. The method also contemplates the outward pulling of the wool away from the center of the skin as distinguished from the pushing operation of the prior art. This permits the operators better to delineate the lines of demarcation between the various grades of wool, particularly when, as in the preferred practice of the method, the skins are moved in a horizontal 45 plane at approximately waist height.

45 The drawing and legends appended thereto illustrate rather diagrammatically the various steps in the preferred practice of the method. Reading from top to bottom, Figures 1-5, inclusive, illustrate the preferred sequence of steps

in the removal of the wool as the skin passes through the various stages of the operation. The arrows indicate the direction of the movement of the skin and also the direction of the wool removal in the various steps of the operation.

In Figure 1, shown at the top of the page, an entire sheepskin is illustrated, all of the wool being still in position thereon and the various grade areas marked off. The skin has been designated generally as 10, the back or main grade as 11, the flanks as 12, the legs as 13, the head as 14 and the rump as 15.

As shown in Figure 2, the grey leg and head wool is removed first, preferably by pulling away from the center of the skin. This is one of the inferior grades and after removal may be deposited in a particular container provided for this purpose.

In Figure 3, the coarse rump wool is shown as being removed preferably by a pair of operators working one on each side of the skin. This wool, although strong, is particularly coarse and it is quite essential that no appreciable part of it be permitted to mingle with the finer grades.

In Figure 4, the stained and shorter flank wools are shown as being removed in a similar way. These wools are of good quality but are usually classified at least a grade lower than the back wool because the fibers are shorter and usually discolored.

In the final step shown in Figure 5, the main grade alone remains and may be removed separately, preferably by pulling from the sides. If at this stage of the operation any of the inferior grades still remain adjacent the main grade the operator removing the main grade can readily separate them at this time and deposit them in their appropriate containers.

After all of the grades have been removed there will still be certain tufts of wool left on the skin due to the uneven action of the depilating agent. These can be removed manually, or preferably, while the skin is still on the conveyor, they may be removed by a mechanical clipping operation.

After the removal of all of the wool the ends of the skin are trimmed off for scrap and the skin is prepared for commercial use.

To those who are familiar with the art it will be apparent that the method of this invention likewise has application to the sorting of the various grades of wool contained in a fleece. In the application of the method to a fleece it is of course not necessary to separate the wool from the skin. However, the fleece may be moved in the same way as illustrated for a skin and the same routine of sorting operations may be performed. In the case of a fleece as in the case of a sheepskin it will follow that the method of the

invention permits a much more accurate sorting operation than would be the case if the wool were simply sorted manually by a single operator while the fleece was laid out before him on a table.

In substance, the method of the invention permits a complete wool pulling operation which is much quicker and cleaner than that practiced heretofore. In particular, the method permits the sorting of the various grades of wool in a much more accurate way than has been possible heretofore. The difficulties experienced in the training of skilled operators are largely avoided because under the preferred practice of the present method each operator performs only a single operation at which he should be able to become skilled in very short order. The removal of the inferior grades of wool first is particularly important since, as previously stated, it is in this way possible to keep the main grade almost entirely free from inferior grades. Even if a portion of the main grade should become mixed with the inferior grades in the initial steps of the method this is not nearly as serious a matter as mixing any portion of the inferior grades with the main grade. The actual physical operation of removal is by this method made materially easier as the operator is performing a natural outward pulling operation rather than a down-hill pushing operation. The lack of direct physical contact between the saturated skin and the operator's body is also a great improvement over the prior methods.

Having described my invention, I claim:

1. In the art of wool pulling and sorting the method which includes the steps of moving a sheepskin in front of a series of operators, each of whom removes the wool from a specific defined area of the sheepskin, the superior main or back grade being removed by the last operator in the series after the prior removal of the inferior grades by the preceding operators in the series.

2. In the art of wool pulling the method which includes the steps of passing a sheepskin along a series of operators, each of whom removes a single grade of wool, the inferior grades next to the outer margins of the skin being removed prior to the removal of the superior centrally located back wool.

3. In the art of wool pulling and sorting the method which includes the successive steps of treating a sheepskin with a depilating agent and then moving the treated skin along a series of operators, each of whom removes a single grade of wool, the inferior grades being all removed in order prior to the removal of the back wool.
